US0D1055880S

(12) **United States Design Patent** (10) **Patent No.:** **US D1,055,880 S**
(45) **Date of Patent:** **** Dec. 31, 2024**

(54) **POWER MODULE**

(71) Applicant: **Delta Electronics, Inc.**, Taoyuan (TW)

(72) Inventors: **Jen-Hsien Wong**, Taoyuan (TW);
Han-Lin Wu, Taoyuan (TW);
Chun-Liang Chiang, Taoyuan (TW);
Tai-Kuang Lee, Taoyuan (TW)

(73) Assignee: **Delta Electronics, Inc.**, Taoyuan (TW)

(**) Term: **15 Years**

(21) Appl. No.: **29/862,863**

(22) Filed: **Dec. 13, 2022**

(51) LOC (14) Cl. **13-03**

(52) U.S. Cl.

USPC **D13/182**

(57) **CLAIM**

The ornamental design for a power module as shown and described.

DESCRIPTION

FIG. 1 is a front, top, and right side perspective view of a power module showing our new design;

FIG. 2 is a rear, top and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line portions in the drawing views are included to show portions of the power module only and form no part of the claimed design.

1 Claim, 8 Drawing Sheets
